UNITED STATES PATENT OFFICE.

THEODORE H. LOW, OF NEW HAVEN, CONNECTICUT.

BOTTLE-OPENER.

1,214,802.

Specification of Letters Patent.

Patented Feb. 6, 1917.

Application filed February 15, 1911. Serial No. 808,842.

To all whom it may concern:

Be it known that I, THEODORE H. LOW, a citizen of the United States, residing at New Haven, in the county of New Haven, 5 State of Connecticut, have invented a new and useful Bottle-Opener, of which the following is a specification.

This invention relates to decappers for opening bottles closed or sealed with caps. 10 Its object is to improve on the present crown stopper extractors especially on those which constitute bent levers of the first order operating by pressing down on the handle.

The improvement aims to provide an 13 opener by which a bottle can be easily opened and its contents poured out by the hand holding the bottle.

My invention consists in providing an 16 opener operable by the pressure on the han- 20 dle obtained by the gripping or squeezing of the fingers of the hand holding the bot- tle. Its object is to decap bottles with the minimum of time, effort and motion. With this object means are provided to adjust 23 easily the opener in operative position on the bottle cap to prevent it from being pushed away therefrom while leaving the lever arm free. Means are further provided to reduce the friction in lifting the cap, to restrict the 26 motion, to retain the hold on the cap after the bottle is opened, and to enable the contents of the bottle to be freely poured out while still holding the bottle. These and other objects are hereinafter illustrated, set 30 forth and explained in the accompanying drawing, description and claims.

The accompanying drawing illustrates the 33 improved opener and forms a part of the specification.

40 Figures 1 and 2 are views in perspective and plan of the preferred type of opener. Figs. 3, 4 and 5, show various forms of head and handle.

As shown in Figs. 1 and 2, the bottle 45 opener is preferably made from one piece of wire. While the head may be of any shape suitable to assist in holding the nib in place under the cap flange without binding the lever arm the preferred form is of re- 50 silient wire having the inwardly disposed nib 1 swaged so as to fit under the edge of the cap flange at preferably approximately 45 degrees since this angle enables both upward and outward pressure to be exerted by 55 the nib on the flange to force the flange clear of the bead encircling the bottle mouth. In

the preferred form of opener the two parts of the wire head 2 extend horizontally from the nib to fit around the cap flange so as to embrace at least a semi-circumference of it. 60 The offsets 3 bent at substantially a right angle are thus removed to the side of the cap away from the nib and are bent in to grip opposite sides of the flange so as to prevent the nib being dislodged by horizontal pres- 65 sure of the gripping hand operating the opener. Both parts of the wire then extend inward as at 4 over the top of the cap and downward to form a fulcrum near the center of the top of the cap. Moreover, the head is adapted to spring over the cap owing to the resiliency of the wire and the nib forced under the cap flange so as to lock the head in place and place the cap flange under 70 initial lifting tension. The head, moreover, 75 grips the cap so as to hold it after the bottle is opened. Any care needed in fitting this form of head on to the bottle cap is amply repaid by subsequent facility in opening the bottle. This form of head may be adapted 80 to any type of opener.

Each part of the wire may be given such a direction that the fulcrum rests on any desired part of the top of the cap though preferably the fulcrum is in the same vertical plane as the gripping side. The fulcrum divides the handle portion from the head portion. From the fulcrum the two parts of the wire are brought together and upward clear of the cap and extend beyond that edge of the cap opposite the nib so as to be spaced clear of the cap flange and extend downward in the direction of the bottle neck and substantially parallel to it. This handle 5 is in such angular relation to the head of the opener that when the head engages a cap sealing a bottle the handle is in such proximity to the bottle neck as to enable the hand to readily encircle and grasp both the bottle neck and the handle. While the opener is in this operative position the handle is sufficiently clear of the bottle neck not to come into contact with it until all necessity for the lever arm has gone. 100

The parts of the wire spread at 5 to enable the handle to be wider and to better fit the bottle neck. The handle extends any desired distance along the bottle neck and has outwardly curving ends at 7 so that on first contact of the handle with the bottle neck this outward end would not rest against the bottle neck. Thus by further movement of 105 110

the operating hand the handle is swung so as to cause the projecting end to come into contact with the bottle neck and thus swing the head clear of the bottle mouth. The ends of the opener meet preferably at 6. The wire is of such resiliency as not to seriously interfere with the rigidity of the lever arm.

The opener is unique in being operable by 10 horizontal pressure of gripping, the hand grasping the bottle neck and opener. Thus, in lifting up the bottle by its neck its weight as well as the natural grip of the fingers and the purchase gained by the grasp of 15 the bottle neck assist in lifting the cap. Thus, a waiter while holding the tray in one hand is enabled to open bottles with the other hand as well as serve their contents. Moreover, bottles may be decapped 20 without removing them from their cases or from the table. There is no lost motion or movement of the arm necessary, merely a tightening of the fingers around bottle neck so that the contents of the bottle are 25 undisturbed, which makes it especially advantageous for ale. All danger of chipping is overcome, since the cap is lifted by gradual pressure and all contact of the nib with the retaining bead is avoided. The lever arm 30 can be increased to any desired extent by extending the handle. Moreover, the improved opener is hygienic, since there is no necessity for the hand being near the bottle mouth, while the cap, being held by the 35 opener, cannot drop on the floor.

Various forms of self-locking heads and of means for locking various forms of nibs in place as well as swinging the heads of openers by the hand operating the openers clear 40 of the bottle mouth are shown in Figs. 3 to 5.

Fig. 3 shows a different shaped head and handle. Here the head 8 does not encircle the cap flange nor grip it. The nib 9 may be 45 bent upward to prevent slipping. The cross piece 10 is fastened under the head to raise the pivot around which the nib swings clear of the bead. The ends 11 of this cross piece may be bent down to grip the cap flange and 50 if necessary bent back to enable such gripping point to lie back of the center of the cap. The end of the handle is opened for the purpose of gripping the bottle neck in the adjusted position. The extreme ends 55 flare out at 12 to guide the gripping portion 13 and insure the ends being in position around the bottle neck before the pressure to raise the cap is applied. As soon as the cap is raised the gripping portion 60 springs around the neck at such tension and angle as tends to cause the gripping portion to assume a right angle position around the bottle neck, and relieve the tension. Thus the head is swung clear of the bottle mouth. 65 The tension of the gripping arm will also

cause the handle to ride up on a tapering neck, as well as enable the opener to hang on the bottle after use.

In Fig. 4 two hooks 14 hook under the inner edge of the flange so as to lock them 70 in place. Since the ends of the head are open, the resiliency of the wire allows the hooks to accommodate themselves to various sizes of caps. The wire of the head extends downward at 15 to enable the fingers 75 of the hand to hold the hook the better in engagement with the cap flange. Springs are shown fastened part way down on the handle at 16 to assist in adjusting the holder and hold it to the bottle neck.

Fig. 5 is similar to Fig. 1 except that the handle is shaped to drop loosely over the cap and bottle neck and remain hanging therefrom after the cap has been forced off.

Having thus described my invention, I 85 claim:

1. A crown cap remover comprising a handle, a fulcrum point adapted to rest on top of the cap and a head rigidly mounted on said handle and having a nib adapted to 90 fit under the edge of the cap flange, said head extending around a portion of the periphery of the cap flange and offset at substantially a right angle therewith.

2. A crown cap remover constituting a 95 bell crank lever comprising a handle spaced clear of the cap and extending downward approximately vertically, a fulcrum adapted to rest on top of the cap and a cap engaging head rigidly mounted on said handle and having a nib fitting under the edge of the cap flange and parts extending therefrom horizontally around at least a semi-circumference of the cap flange then bending up over the top of the cap, such bend being 100 adapted to grip the flange so as to protect the nib from slipping away from the cap flange on exerting horizontal pressure on the handle.

3. A crown cap remover comprising a cap 110 engaging and cap lifting member, and a downwardly disposed operating lever rigid thereto, and means for locking the cap-engaging and cap-lifting member to the bottle cap so as to resist inward pressure tending to force the cap engaging member away from the bottle cap, while leaving the lever arm free.

4. A bottle opener comprising a cap-engaging head, a fulcrum resting on top of the cap and a handle in such angular relation to the head that when the bottle opener is in operative position the handle extends downwardly substantially parallel to the bottle.

5. A bottle opener comprising a cap-engaging head fulcruming on top of the cap and a handle extending downward and spaced from the bottle neck so closely as to be readily grasped by a hand encircling the 130

bottle neck and so far as to keep clear of contact with the bottle neck until the cap has been lifted from the bottle mouth.

6. In a bottle opener, a cap-engaging head 5 locked to the bottle cap against horizontal pressure and having an inwardly disposed nib engaging under the edge of a portion of the cap flange, a fulcrum resting on top of the bottle cap, a bell crank lever handle 10 spaced clear of the cap flange and bottle on the side opposite to the flange-engaging nib and adapted to cause the nib to force a portion of the flange clear of the retaining bead on the bottle mouth by horizontal pressure 15 on the outside of the lever handle.

7. In a bottle opener, a cap-engaging head having an inwardly disposed nib fulcruming on top of the cap, and a handle bent down so as to come into contact with the bottle neck 20 immediately after the bottle has been opened, thereby preventing unnecessary movement of the bottle opener after the cap has been lifted.

8. In a bottle opener, a cap-engaging and 25 cap-lifting head with an inwardly disposed nib, a fulcrum resting on top of the cap and a handle spaced from and extending downward along a bottle neck and constituting a bell crank lever adapted to force the cap 30 from the bottle mouth by pressing the handle into contact with the bottle neck.

9. In a bottle opener, a cap-engaging head having a flange-engaging nib, a fulcrum resting on top of the cap over its outer periphery and a handle rigidly carried on said 35 head extending substantially parallel to the bottle axis.

10. A crown cap remover comprising a cap 40 engaging and cap lifting member, and a downwardly disposed operating lever arm rigid therewith and adapted to lift the bottle cap by horizontal pressure applied to said lever arm.

11. In a bottle opener, a cap-engaging 45 head with a flange-engaging nib, a fulcrum resting on top of the cap and a handle bent downward approximately parallel with the bottle and means on the handle for rotating such cap-engaging head clear of the bottle 50 mouth after opening the bottle.

12. In a resilient wire bottle opener, a 55 head having an inwardly disposed nib swaged thereon and parts extending around at least a semi-circumference of the cap and bent upward at substantially a right angle to grip the outside of the flange and then inward toward each other and downward to form a fulcrum on top of the center of the cap and in the same vertical plane as the 60 gripping portion and then upward to form

a handle and to clear the cap and outward away from the nipping part so as to clear the cap flange and downward in the direction of the bottle axis and spaced from the bottle neck so that the handle and the bottle 65 neck can be easily gripped by the same hand.

13. A crown cap remover having a cap engaging head, a nib engaging under the edge of the cap flange, and a handle bent downward into substantially axial alignment 70 along the diametrically opposite periphery of the cap flange and bottle and adapted to lift the cap by being pressed inward toward the bottle.

14. A crown cap opener comprising a head 75 fulcruming on top of the crown stopper and engaging under the edge of a portion of the cap flange, a lever operating handle bent downward into spaced relation with the opposite side of the cap flange and bottle, and 80 resilient means for yieldingly engaging the cap flange.

15. In a crown cap remover, a cap engaging and cap lifting head, and a lever handle adapted to come into contact with the bottle 85 after the cap has been lifted and to throw the head clear of the bottle mouth after such contact.

16. A crown cap remover comprising a head resting on top of the cap, a nib projecting therefrom so as when in operative position to engage under the edge of a portion of the cap flange, an operating handle bent downward on the diametrically opposite portion of the cap flange, means to guard the operating handle from binding on the cap and 90 means to prevent the nib from being forced out of operative position on the application of pressure to the outside of the operating handle. 100

17. A crown cap remover comprising a cap engaging and cap lifting head fulcruming on the top of the bottle cap and a lever handle depending therefrom adapted for contact with the bottle after lifting the cap and having 105 its lower end curved outwardly.

18. A crown cap remover comprising a cap engaging and cap lifting member and a downwardly disposed lever handle operable by pressure inward toward the bottle and 110 means to guard the handle against contact with the bottle until after the cap is lifted.

In testimony whereof I hereunto affix my signature in the presence of two witnesses.
